CLAIM

The ornamental design for an oxygen chamber, as shown and described.

DESCRIPTION

FIG. 1 is a top, front, right side perspective view of an oxygen chamber, showing our new design;

FIG. 2 is a bottom, rear, left side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of a portion labelled 9 in FIG. 1;

FIG. 10 is an enlarged view of a portion labelled 10 in FIG. 1;

FIG. 11 is an enlarged view of a portion labelled 11 in FIG. 1;

FIG. 12 is an enlarged view of a portion labelled 12 in FIG. 2; and,

FIG. 13 is an enlarged view of a portion labelled 13 in FIG. 2.

The dash-dot-dash broken lines denote the boundaries of the enlarged detail views and form no part of the claimed design.

1 Claim, 13 Drawing Sheets
